UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LET-BACK FOR LOOM TAKE-UPS.

Application filed October 4, 1923. Serial No. 666,594.

To all whom it may concern:

Be it known that I, WALTER H. WAKEFIELD, a citizen of the United States, residing at Worcester, in the county of Worcester 5 and State of Massachusetts, have invented a new and useful Let-Back for Loom Take-Ups, of which the following is a specification.

This invention relates to let-back mechanism for loom take-up motions and an object of the invention is to relieve the filling stop motion of the strain of disconnecting the take-up mechanism from its drive when a fault in the filling occurs.

Take-up motions are ordinarily actuated by some regularly moving part of the loom and receive either a constant or intermittent motion by means of which a train of gearing rotates the take-up roll in a steady forward direction. When a fault in the filling occurs it is necessary for the weft to be withdrawn and unless the take-up roll is moved backwardly an amount to compensate for the withdrawn weft, a thin place will appear in the cloth. So-called let-back motions are customarily employed to permit the take-up roll to have this retrograde motion, but of course it is necessary before the roll can move back to disconnect the gearing connected therewith from the driving mechanism. In the type of let-back motion to which my present invention relates, the strain of disengaging the take-up motion from its drive has ordinarily been assumed by the filling stop motion, but where the fabric is heavy it is found that the strain is so great that the stop motion cannot be relied upon to effect proper disengagement of the driving parts.

In an application filed by Joseph Wilkinson June 18, 1923, Serial No. 645,968, there is shown a motion somewhat similar to the motions disclosed herein, but in said application the strain already mentioned is transferred to the filling stop motion and it has been found necessary to make certain parts of the stop motion of heavier material than is necessary in the present instance, and it is an object of my invention to provide a let-back mechanism wherein the several parts may be made of relatively light material compared with the work to be done.

It is a further object of my invention to employ connections between the disengag-

ing mechanism and some adjacent fixed part 55 of the loom, whereby the filling stop motion is called upon merely to position the connections, while the actual strain of disengaging the parts is transferred to the fixed part. 60

With these and other objects in view, which will appear as the description proceeds, my invention resides in the combination and arrangement of parts hereinafter set forth and more particularly claimed. 65

In the drawings, wherein one form of my invention is shown,

Fig. 1 is a side elevation of portions of a loom having my invention applied thereto.

Figs. 2 and 3 show certain parts illustrated in Fig. 1 in different positions.

Fig. 4 is a horizontal section on line 4—4 of Fig. 1, and

Fig. 5 is a view similar to Fig. 4, but taken on line 5—5 of Fig. 1 and showing 75 certain connections with the filling stop motion shaft.

Referring particularly to the drawings, there is shown a loom side 10 having a filling stop motion 11 provided with a fork 80 12 and tail 13 movable therewith. A lever 14 pivoted at 15 of the loom frame has a foot 16 positioned for engagement with a cam 17 fastened to the bottom shaft 18 of the loom. The upper arm 19 of the lever 85 14 moves under the tail 13 as the lever rises and falls under the action of cam 17. Extending across the loom is a filling stop motion shaft 20 which has secured thereto an arm 21 which extends in front of slide 22 90 on which the filling fork 12 is pivotally mounted.

The crank shaft 23 has fixed thereon an eccentric 24 surrounded by an eccentric strap 25, by means of which a horizontal reciprocating motion is given feed pawl 26. Rotatably mounted on a fixed center, as at 27, is a ratchet wheel 28, the teeth of which are successively engaged by pawl 26 and moved in a clockwise direction as viewed in Fig. 1 100 when the crank shaft 23 is rotating. A hold pawl 29 is pivoted to the frame at 30 and serves to prevent retrograde movement of ratchet 28 when the pawl 26 is moving forwardly. 105

A stand 31 is secured to the loom side and has pivotally mounted thereon an arm 32 to the outward end of which is pivoted

let-back pawl 33 which latter is normally in contact with one of the teeth of the ratchet 28, while the arm 32 is spaced from stop 34 located immediately in front of said arm. 5 The matter thus far described is of the usual construction and no claim is made therefor.

My improvements consist of an arm 40 fastened to the shaft 20 as shown in Fig. 10 5 and from the rear end of which depends connector 41. A cam arm 42 is loosely mounted upon the shaft 20 between arm 40 and a collar 43 fastened to said shaft. For the purpose of raising cam arm 42 I 15 provide a toggle joint, one member 44 of which is pivotally connected to a fixed stud 45 and the other member 46 of which is pivotally connected to the lower end of connector 41 as at 47 and also the cam arm 20 42 at 48. The cam arm 42 is normally in the position shown in Fig. 1 with the toggle joint broken and is so positioned as to be 25 out of the path of the pawl 26 when the latter is in its foremost position. 30 When a fault in the filling occurs, arm 21 will move to the position shown in Fig. 2 and arm 40 will accordingly be raised, the result of which is to straighten the 35 toggle. As this occurs the cam arm 42 is moved to the raised position shown in Fig. 2. The parts are so timed that the pawl 26 moves rearwardly at the time that arm 19 moves forwardly, the result of which is that hold pawl 29 is free to be raised 40 from the ratchet wheel 28 when the toggle is straightened. For the purpose of raising pawl 29 a pin 49 is secured to cam arm 42 and passed under said holding pawl to raise the latter to the position shown in Fig. 2.

By referring to Fig. 1 it is seen that cam 45 17 is provided with a dwell, the purpose of which is to hold the arm 21 forwardly for an appreciable interval of time. During this interval of time, the pawl 26 is moved forwardly and a lateral extension 50 formed thereon is caused to ride upon the upper face of cam arm 42, the effect of this being to disengage the pawl 26 from ratchet wheel 28. When this takes place

the tension of the cloth moves the ratchet wheel counterclockwise and the let-back pawl 33 moves forwardly until arm 32 is arrested in its motion by stop 34. The parts will then assume the position shown 55 in Fig. 3. After the filling fault has been corrected arm 21 and slide 22 are moved to their normal rearward position either by disengaging the tail 13 from the arm 19 or by turning the loom over until foot 16 60 leaves the dwell 47 on cam 17.

From the foregoing it will be seen that the cam arm is raised to operative position with the driving pawl by means of connectors from the filling stop motion, but that the strain and pressure on said cam arm incident to the disengagement of the drive pawl and the ratchet wheel is transferred to some fixed part of the loom 65 and not the filling stop motion. 70

Having described one form of my invention it will be apparent that changes and modifications may be made therein by those skilled in the art and I do not wish to be limited to the specific structures 75 illustrated, but what I do claim is: 80

1. In a take-up for looms having a filling stop motion, a reciprocating take-up actuating pawl, a cam normally out of the path of the pawl, a toggle joint interposed between the cam and a fixed point on the loom, and connections between the stop motion and the toggle to move said cam into the path of the pawl when the stop motion operates. 85

2. In a take-up for looms having a filling stop motion, a reciprocating take-up actuating pawl, a cam normally out of the path of the pawl, a toggle joint interposed between the toggle joint and stop motion 90 to straighten the toggle joint when the stop motion operates to move said cam in the path of the pawl, said connection resetting the toggle and moving the cam to inoperative position when the stop motion is restored to normal running position. 95

In testimony whereof I have hereunto affixed my signature.

WALTER H. WAKEFIELD.
